(57) **CLAIM**

The ornamental design for a vehicle traction mat, as shown and described.

DESCRIPTION

FIG. 1 is a top view of the vehicle traction mat;
FIG. 2 is a bottom view of the vehicle traction mat;
FIG. 3 is a top rear perspective view of the vehicle traction mat;

FIG. 4 is a left side view of the vehicle traction mat, the right side view of the vehicle traction mat being a mirror image of the left side view of the vehicle traction mat;
FIG. 5 is a right side perspective view of the vehicle traction mat;

FIG. 6 is a rear view of the vehicle traction mat;
FIG. 7 is a front view of the vehicle traction mat; and,
FIG. 8 is a left side view of the vehicle traction mat, with a vehicle wheel of a vehicle on the vehicle traction mat in typical application thereof.

The broken lines of the rectangular section of the claimed design in FIGS. 1-5 and 8, illustrate portions of the vehicle traction mat that form no part of the claimed design. Additionally, the vehicle wheel illustrated in FIG. 8, represents environmental structure that forms no part of the claimed design.

1 Claim, 8 Drawing Sheets
